CIRCULAR KNITTING MACHINE

Ivan W. Grothey, Laconia, N. H., assignor to Scott & Williams, Incorporated, New York, N. Y., a corporation of Massachusetts

Application December 9, 1937, Serial No. 179,005

8 Claims. (Cl. 66—168)

This invention relates to independent needle circular knitting machines, and more particularly to means for removing lint from around the knitting elements in such machines.

In certain types of independent needle circular knitting machines, float stitches or reverse plated stitches for patterning are produced by deflecting needles radially inward. It has been found that the space between the upper part of the needle when not deflected and the bottom of the slot in which the needle lies tends to become clogged with lint, especially when knitting wool. This clogging eventually reaches the point where the needles cannot be bent sufficiently to cause the desired deflection. It is one object of this invention to cure this difficulty by removing the lint periodically and automatically in the operation of the machine. It is characteristic of the invention that a jack is provided for this purpose behind the needle and in the same slot.

In the drawings,

Fig. 1 is a vertical section through a needle cylinder embodying my invention, the jack on the right side of the machine being shown at lint-ejecting level, and the jack on the left side being shown at fulcrum level;

Fig. 2 is a development of the path of the needles and jacks, viewed from the inside of the cylinder, the needles and jacks moving from left to right as they appear in this figure; while

Fig. 3 is a perspective view of the upper end of a cleaning jack of rectangular transverse cross section.

In the ordinary circular knitting machine having independent needles which are deflected inwardly for patterning purposes, the needles are each mounted in a slot on the periphery of the needle cylinder. Heretofore the slot has been deeper at the upper end of the cylinder in order that the needles may be bent radially inward when patterning. It is in this pocket that the lint collects and prevents the needle being deflected sufficiently to cause the desired stitch to be made. The shoulder of the slot where the needle bends over it as a fulcrum also tends to become worn. To cure these two difficulties, I place a vertically movable jack in the slot behind each needle which is to be deflected, and so shape and manipulate this jack that it can act both as a lint-ejecting element and also as a fulcrum point for the bending of the needle.

Referring specifically to the drawings, the machine has the usual bedplate B and needle cylinder 260 supported thereon. In the drawings there is the usual main horizontal gear ring 30 acting

through its sleeve 251 to turn the needle cylinder, as usual. The needle cylinder is moved vertically by pins 256 in order to change the length of stitch. The periphery of the needle cylinder is slotted as usual. Each slot contains a pattern jack 5 136, a needle jack 380, an independent latch needle N and a novel cleaning jack 273, to be described later. The pattern jacks 136 are selected and then raised by a cam 741 which is part of the stationary cam ring 271 carried on the jack cam plate 270, all 10 in the same general manner as shown and described in the patent to Ivan W. Grothey, No. 1,678,385, dated July 24, 1928, and the patent to Albert E. Page, No. 1,969,853, dated August 14, 1934. On top of the needle cylinder may be a fulcrum ring 276. Above the cylinder are located the usual sinker dial 295, inside sinker ring 248 and the sinker cap 300. The sinkers S are carried by the inside sinker ring 248 and sinker dial 295, while the needles project upwardly between the sinkers. 15 20 This much of the construction is standard, with the exception of the fulcrum ring.

Needle deflection can be used to produce float patterns or reverse plated patterns. In the example shown in the drawings, reverse plated patterns are produced by deflecting radially inward the needles where reverse plated stitches are desired. The general type of mechanism for accomplishing this is shown in the British Patent No. 438,639 to Standard-Trump Bros. Machine Co. 30 This mechanism includes horizontal pressers 278 carried in the lower part of the sinker dial and pressing radially inward against presser jacks 277 lying in the slots with the needles.

In the construction of the said British Patent 35 No. 438,639, it is necessary to cut back the upper end of the slots in the needle cylinder to give room for the descent of the needle when it is deflected. It is this slot which causes trouble by reason of lint packing behind the needle until it 40 is impossible to deflect the needle head properly. According to the present invention, this vacant space is cleaned by putting behind the needle a cleaning jack 273 which is raised up by the pattern jack 136 when the latter is selected. At this 45 time the new jack is raised to a point where it is just about opposite, or a slight distance above, the sinker ring 248 on top of the needle cylinder 260, as shown at the right side of Fig. 1. This pushes out any lint which may have accumulated in the space while the new jack was down. After the jack has been raised to lint-ejecting level, it is drawn down again until its upper end is at the level where the needle is flexed for reversing. It will be seen that when 50 55

the jack is in this position it serves as a fulcrum point for the needle, and since the jack is removable the fulcrum or deflecting point is removable and can be replaced if wear occurs. In the drawings the operating butt of this new cleaning jack is designated by the number 274. Its lower end always contacts the upper end of the pattern jack 736, in the embodiment shown in the drawings. The usual needle jack 380 rests on the butt 274 of the cleaning jack and is therefore lifted when the cleaning jack is lifted. The upper end of this needle jack underlies the operating butt of the needle. It will be obvious that when the cleaning jack is raised a sufficient distance the needle will in turn be raised. The presser jack 277 being above the foot of the needle, it will be raised along with the needle if the latter is raised sufficiently high. However, this presser jack has an operating butt of its own and can be lowered separately.

It is important that the upper end of the cleaning jack be properly shaped, as otherwise it would only serve to jam the lint further down in back of the needle. In order that it may function properly and keep the lint above itself, the upper end of the cleaning jack 273 preferably corresponds to the maximum width of the jack and is so formed as to provide a substantially flat surface 275 which extends at an angle not substantially greater than 90° with respect to the front and rear faces of said jack, one example of such a construction being shown in Fig. 3. There is thus provided an outer edge 275a which, in one position of the jack, serves as a fulcrum for the needle N, and an inner edge 275b which corresponds substantially in length to the width of the needle slots in the needle cylinder 260 and to the width of the slots in the sinker ring 248. In other words, the upper end 275 of each cleaning jack 40 is disposed substantially at a right angle to the length of each jack and is of a width corresponding substantially to the width of each of the slots in the needle cylinder 260 and in the sinker ring 248, and is of a depth corresponding substantially to the depth of each of the spaces existing between the inner face of each needle N and the wall defining the bottom of each of the slots in the needle cylinder 260 and in the sinker ring 248. Hence the jack contacts the inner face 50 of the needle and the wall defining the bottom of the slots in the needle cylinder 260 and in the ring 248 during the reciprocating movements of said cleaning jack. The shape of the upper end 275 of each cleaning jack must be such as to retain the lint rather than let it pass below and jam. By having no portion of the upper end 275 of the jack extend a substantial distance above the outer and inner edges 275a and 275b, respectively, when the jack is raised to lint-ejecting 60 level, there is no portion of the jack which will project upwardly into the fabric in the throats or ledges of the sinkers. In Fig. 2 the needles N have been broken away for a short distance below and above the upper ends 275 of the 65 cleaning jacks in order that the positions of the upper ends of the cleaning jacks may be more apparent. The needles and associated elements are moving from left to right in this figure. When a pattern jack 736 has its lower end rocked 70 radially into the cylinder, it misses the raising cam 741 and remains at the height at which it approaches that cam. The upper end of the cleaning jack in this instance remains at the same level until the butt 381 of the needle jack 75 above it contacts a cam surface 279 and brings

it down a short distance. In this position the upper end 275 of the cleaning jack is at the so-called fulcrum level opposite the upper face of the fulcrum ring 216. The pattern jack stays at this level until it is being prepared for selection on the next revolution just prior to the raising cam 741. The needles N associated with such non-selected pattern jacks will, by virtue of their operating butts n, be cleared by the leading stitch cam 361 and pass through the regular knitting wave under cams 357, 360, etc., as usual, all needles thereafter taking the dotted path indicated in Fig. 2.

Assuming that a pattern jack has not been depressed or selected out, its operating butt 733 will ride up the raising cam 741. This will raise not only the pattern jack but also the needle jack 380, the needle N and the presser jack 277. This movement raises the needle butts n to a level where they will be maintained at a given height 20 and then raised by a cam 161 to position the presser jacks, the needles being thereafter lowered by cam 162 to a level where they will pass under the top center cam 357, as usual. In the meantime, the needle jacks and the pattern jacks 25 have been lowered by the cam 279 to the same level as the non-selected jacks, and with them go the cleaning jacks 273 whose butts 274 underlie the butts 381 of the needle jacks. The needles and presser jacks raised by the needle jack 380 30 are lowered by their own operating butts after the cleaning jacks and the pattern jacks have descended. The coordination and operation of the horizontal pressers 278 with the presser jacks 277 are practically identical with that shown in the 35 British patent to Standard-Trump Bros. Machine Co., No. 438,639, above referred to, except that a small shoulder 163 may be formed at the outer edge of the presser jack 277 to contact the upper edge of the horizontal presser 278 and prevent a 40 presser jack from being dragged down ahead of the proper time by frictional contact with descending needles. It will be observed that the upper end of the presser jack which contacts the needle for deflection does so at a level above the 45 fulcrum level of the cleaning jack and that the cleaning jack takes the pressure of the bending.

It will be observed that by this construction I not only have provided a fulcrum point which is easily changed in case of wear, but that I have 50 provided a construction in which there is no vacant space behind the needle below the top of the needle cylinder, and the space behind the needle above this level is cleaned of lint at each revolution of the cylinder.

Any manipulation of the cleaning jacks and any configuration of the upper ends 275 of said jacks is satisfactory as long as they are at the proper level for deflection of needles and said upper ends are so shaped as to prevent lint from 60 collecting behind the needles, either between the needle and the jack or between the jack and the back of the slot or sinker ring.

Many modifications which do not depart from the scope of my invention will occur to those 65 skilled in the art.

What I claim is:

1. In a circular knitting machine, a slotted needle cylinder, independent needles in said slots and jacks in said slots in back of the needles, the upper end of each jack being formed to provide a surface disposed in a plane extending at substantially a right angle to the length of the jack and with an outer edge contacting the inner face of the adjacent needle and an inner edge con- 75

5 tacting the wall defining the bottom of the adjacent slot in the needle cylinder to prevent lint from above wedging behind the needles, in combination with means adapted to raise the jacks to lint-ejecting level periodically.

10 2. In a circular knitting machine, a slotted needle cylinder, independent needles and lint-ejecting jacks in said slots, the jacks being in back of the needles and each having an upper surface disposed in a plane extending at substantially a right angle to the length of the jack and of a width corresponding substantially to the width of the shank of said jack, in combination with means adapted to raise the jacks to lint-ejecting 15 level periodically.

15 3. In a circular knitting machine, a slotted needle cylinder, independent needles in said slots and lint-ejecting jacks in said slots in back of the needles, each jack having an upper surface disposed in a plane extending at substantially a right angle to the length of the jack and of a width corresponding substantially to the width of the shank of said jack, in combination with means adapted to raise the jacks selectively in 20 25 a lint-ejecting wave as the selected needles are being raised to take yarn.

20 4. In a circular knitting machine adapted to make special stitches by needle deflection, a needle cylinder, independent needles and jacks in slots 30 therein, the jacks being at the bottoms of the slots, the upper ends of each of said jacks being disposed in a plane extending substantially at a right angle to the length of the jack and including a front edge of a length corresponding substantially to the width of the shank of said jack, said upper ends of the jacks serving to keep lint 35 above the jacks and said front edges of said upper ends of said jacks serving as fulcrums for needle deflection, in combination with means to raise the jacks to lint-ejecting level and to place them in fulcrum position.

40 45 5. In a circular knitting machine, a needle cylinder with slots therein, independent needles in said slots, jacks in at least some of said slots in back of the needles and having operating butts

below the needles, the upper end of each jack corresponding in width and depth to the shank thereof and being disposed at an angle not substantially greater than 90° with respect to the length of the jack to prevent the passage of lint 5 below it, in combination with means adapted to move the jacks to lint-ejecting level whereby the needles are raised.

6. In a circular knitting machine, a needle cylinder with slots therein, independent needles 10 in said slots, and needle jacks in said slots below said needles, in combination with cleaning jacks in at least some of said slots in back of the needles and having operating butts below the needle jacks, the inner and outer edges of the upper end 15 of each jack presenting, respectively, a lint-catching edge to the back of the slot and to the back of the needle, and means adapted to raise selected jacks to lint-ejecting level at each revolution of the machine. 20

7. In a circular knitting machine; a slotted needle cylinder; a series of webholders above said cylinder; independent needles in the cylinder slots; and lint-ejecting jacks in the cylinder slots, the upper end of each jack being substantially 25 flat and extending substantially at right angles to the length of the jack and presenting an inner lint-catching edge to the back of the slot; in combination with means adapted to raise the upper ends of the jacks above the cylinder slots to 30 about the level of the throats of the webholders to eject lint.

8. In a circular knitting machine, a slotted needle cylinder, a series of webholders above said cylinder, independent needles in the cylinder 35 slots, jacks in the bottom of the cylinder slots, and means to press the hook ends of the needles radially inward, in combination with means adapted to raise the tops of the jacks above the cylinder slots to about the level of the throats of 40 the webholders to eject lint and to a level where the upper edge of each jack can act as a fulcrum for needle deflection by said pressing means.

IVAN W. GROTHEY. 45
